UNITED STATES PATENT OFFICE.

WINTHROP K. HOWE, OF ROCHESTER, NEW YORK, ASSIGNOR TO GENERAL RAILWAY SIGNAL COMPANY, OF GATES, NEW YORK, A CORPORATION OF NEW YORK.

TRAIN CONTROL.

Application filed October 7, 1922, Serial No. 593,073. Renewed November 23, 1927.

This invention relates to automatic train control systems, and particularly to a system wherein a plurality of distinctive intermittent control influences are transmitted from the trackway to a moving vehicle.

In providing apparatus for automatically controlling a train, or for bringing it to a stop if it exceeds a safe speed at a particular point along the track under either clear or danger traffic conditions ahead, it is found desirable to limit the train to a certain speed continuously for a certain distance after which the speed limit may be still more restricted until the speed is reduced to a safe value at that particular point along the trackway. If, for instance, it is desired to bring the train to a safe low speed of, say, ten miles per hour, it is desirable to gradually bring the train down to this speed by successive steps of decreasing speed limits which are enforced by distinctive control influences from the trackway until this low speed limit is reached. This manner of bringing the speed down is desirable, because the successive decreasing speed limits may be enforced relatively close together or far apart, in accordance with the ability of the train to stop in this particular section of the trackway. For instance, in a section where there is a steep down grade, the successive lower speed limits must be enforced further apart on account of the longer braking distance necessary on down grade to allow the engineer by proper control of the train to prevent an automatic brake application, whereas on an up grade and around a curve a much shorter braking distance will be sufficient, and the successive speed limits may be enforced much closer together. Further, a speed limit may be enforced at a particular point in a block, entirely independently of a preceding speed limit, by a system of this kind.

In applying automatic devices for controlling the movement of trains in accordance with traffic and trackway conditions in advance, it is desirable, for well-known reasons, to use the regular air brake system already on the train; but difficulties are encountered in enforcing an automatic brake application with safety and in a manner so that it can not be forestalled by the engineer. In order to make a brake application by suitable automatic apparatus acting upon the usual air brake equipment, it is necessary to vent air from the brake pipe. Since, however, the en-

gineer's brake valve when in its usual running position continually feeds air into the brake pipe through a feed valve, it is advisable to do more than merely open the brake pipe to atmosphere to cause a proper brake application, that is, a brake application which will not enable the triple valve located on the cars of the following train to move into emergency and apply the brakes so severely so as to endanger the railway equipment. In addition to the undesirable feature of the automatic air brake system which allows air to pass through the feed valve into the brake pipe under normal conditions, that is, with the brake valve in the running position, there is another problem to be taken into consideration, namely, the ability of the engineer to move the brake valve to the release position when an automatic brake application has occurred, and by so doing connect main reservoir pressure to the brake pipe for the purpose of partially or wholly preventing such an automatic brake application.

With the above and other considerations in mind, the principal objects and purposes of the present invention contemplate the provision of suitable devices on the railway vehicle which are adapted to be inductively influenced by suitable traffic controlled devices along the trackway for transmitting distinctive control influences through an air gap, and without physical contact between such devices; to provide apparatus on the vehicle which will set up permissive speed limits corresponding to these distinctive control influences, each speed limit persisting until changed by the reception of another control influence; to provide a brake applying device which will act upon the regular air-brake system through the agency of the regular engineer's brake valve and which will apply the brakes automatically whenever operated, irrespective of an effort on the part of the engineer to prevent such brake application; and to provide means whereby an automatic application of the brakes of the vehicle will not take place, provided the engineer is applying the brakes or has applied the brakes to a predetermined extent and keeps them on to this extent until the speed is safe, whereby the step-by-step or saw-tooth speed limits may be smoothed out, so to speak, thereby allowing the train speed to exceed the permissive speed when it is first enforced, and whereby the action of the brakes themselves will

bring the speed below such permissive speed limit before the point along the track will be reached where the next lower speed limit will be enforced.

5 A further important object and purpose of this invention is to provide an organization of parts constituting a speed control system which, while affording the engineer all reasonable opportunity and latitude to control 10 the train himself, will automatically apply the brakes in case the train is not being properly controlled and also impose a suitable penalty upon the engineer for permitting the automatic brake applying mechanism to work. In other words, the system embodying 15 this invention is designed with the idea of maintaining as far as possible the vigilance and care with which engineers with rare exceptions observe and act upon the indications 20 of the block signals, in order that the ultimate safety of the train is safeguarded by the vigilance and care of the engineer and efficiency and dependability of the block signal system in the first place, supplemented by 25 the protection afforded by the automatic speed control equipment. The penalty imposed on the engineer for his neglect or misjudgment in allowing the automatic brake applying mechanism to work may take various 30 forms, such as subsequent discipline based upon recording each automatic brake operation; but it is preferred to use what may be termed a self-inflicted penalty, enforced at the same time as the default by compelling 35 the engineer to bring his train to a stop in order to proceed in the event that the automatic mechanism causes a brake application.

As previously explained, it is contemplated in accordance with this invention that the 40 permissible limiting speeds will be set up to conform with distinctive control influences received from the trackway at the appropriate points; and since the number of these distinctive influences that can be provided 45 in a practical fashion is limited, the different speed limits will vary considerably and will only roughly approximate the speeds at which the train may safely run. Consequently, if the engineer controls a speed of his train 50 in the ordinary way in slowing down in obedience to a caution signal, it may well happen that, while the engineer is properly regulating the speed of his train, he will exceed the permissible speed limits set up by 55 the automatic system; and it is proposed in this invention to obviate this difficulty by constructing the car apparatus in such a way that the engineer, by applying the brakes himself and maintaining that brake application until the speed has been safely reduced, 60 may avoid the automatic brake application and the resultant penalty.

To provide the brake applying device mentioned, it is contemplated to modify the 65 usual engineer's brake valve of the standard

automatic air-brake system in a manner so that the rotary valve member thereof can be actuated to the service or emergency position by direct engagement of parts, but can not be moved to the release position by such direct engagement, but merely through the medium of an intervening initially tensioned spring, providing such movement is not opposed by a suitable automatic brake valve operator which is moving toward, or is holding this valve in the service brake applying position.

70 Further objects, purposes, and characteristic features of the invention will appear as the description thereof progresses.

80 In describing the invention in detail, reference will be made to the accompanying drawings, in which:

Figure 1 illustrates a portion of a railway 85 track along which are provided suitable inductive influence transmitting devices for transmitting distinctive control influences to suitable car-carried equipment, and showing a step-by-step speed distance curve enforced by such trackway devices;

90 Fig. 2 illustrates in a diagrammatic manner car-carried equipment adapted to cooperate with the trackway equipment shown in Fig. 1 to enforce speed limits in accordance with such speed distance curve;

95 Fig. 3 is a plan view of the usual engineer's brake valve provided with an automatic brake valve operator embodying a feature of the present invention, portions thereof being shown in section, and taken on the line 3—3 100 of Fig. 4;

Fig. 4 is a partial section taken on the line 4—4, Fig. 3, as viewed in the direction of the arrows;

Fig. 5 is a cross section taken on the line 105 5—5 of Fig. 4; and

Fig. 6 shows a car-carried circuit arrangement substantially the same as that shown in Fig. 2 but employing modified influence receiving elements, and modified track elements 110 adapted to cooperate therewith.

The preferred embodiment of the present invention relates particularly to means for transmitting influences, which are distinctive in character, from suitable trackway devices 115 located unsymmetrically with respect to the track, so that the movement of a train equipped therewith when moving against the normal direction of traffic will not be affected thereby, and which communicate with a single car-carried device adapted to cooperate therewith. The trackway equipment for such a system is shown in Fig. 1, which shows the usual rails 1 of a railway track divided into blocks by insulated joints 2, the block I and the adjacent ends of two other blocks H and J being shown. Since the several devices in each block are the same, they have been given the same reference characters with distinctive exponents. The block I, as shown, is 120 125 130

provided with a track battery 3 and a track relay 4 to provide the usual closed track circuit control. The influence transmitting devices of a train control system embodying the present invention comprise in general a short U-shaped knock-down track element T^a at a point along the track where the first restriction in speed is to be enforced under caution traffic conditions, a longer U-shaped influence transmitting track element T^b located at a point where the next lower restrictive speed is to be enforced, and a three-legged trackway element T^c where the third and next lower restrictive speed is to be enforced, another resetting track element TR being provided at the end of a block for removing the restrictions enforced by any, or all, of the track elements T^a, T^b and T^c, providing the next block in advance thereof is clear.

The track element T^a comprises a U-shaped core 5, preferably of laminated magnetic material, terminating in enlarged pole pieces 6 and provided with a coil 7, whereas the track element T^b comprises a similar U-shaped core 8 terminating in enlarged pole pieces 9, which are spaced substantially twice the distance between pole pieces 6, and is also provided with a coil 10. The track element T^c comprises a three-legged core having a back yoke 11 having extending legs 12, 13 and 14, each of which terminates in an enlarged pole piece 15. This track element T^c is provided with a coil 16 on each side of the leg 13 on the back yoke 11, the coils 16 being connected in series and controlled in the same manner as the coils 7 and 10.

Adjacent each of the track elements T^a, T^b and T^c is provided a repeater line relay 17, having a front contact 18 connected across the coils on these respective track elements. These repeater relays 17 are connected between a line wire 19 and a common return wire C (not shown), and are energized from a suitable source of energy controlled by a front contact 20¹ of the track relay 4¹ of the next block in advance, having its other terminal connected to said common return wire C. It should be noted that under clear traffic conditions of the block J each of the track elements T^a, T^b and T^c will have their coils closed in a deenergized circuit which is preferably of low resistance.

The resetting track element TR comprises a U-shaped core 21 of laminated magnetic material terminating in pole pieces 22, and provided with a coil 23 on its back yoke. This resetting track element TR at the exit end of the block is under normal conditions, that is, when the next block in advance is clear, energized by the battery 24 through a circuit which may be traced as follows:—beginning at the battery 24, wire 25, front contact 26¹ of the track relay 4¹, wire 27, coil 23 of the resetting track element TR, wire 28 back to the battery 24.

The system is preferably used in connection with the usual fixed signals, and these signals may be of the semaphore, color-light, position-light, or other suitable type; and in the simplified arrangement shown in Fig. 1, three-position semaphore signals Z have been shown in a conventional manner without illustrating their well-known control circuits and devices, it being understood that these semaphore signals will indicate clear, caution and stop in the usual way dependent upon the presence and absence of trains in the corresponding and the next block in advance.

The several car-carried devices which co-operate through suitable circuits to enforce several distinctive speed limits, by cooperation with the trackway devices shown in Fig. 1, will first be separately referred to, after which the manner in which they cooperate will be described in detail. Of these devices the automatic brake valve operator will first be described in detail.

Brake valve operator.—Referring to Figs. 3 to 5, the automatic brake valve operator 90 consists of a casing 30 provided with a tubular extension forming an air cylinder 31. This operator casing 30 is provided with a flange 32 corresponding to the flange of the usual engineer's valve cover plate, and is bolted to the casing 33 of the usual engineer's brake valve. This casing 30 is provided with a partition 34, having a flange 35 to form a bearing. The usual rotary valve 36 is shown extending into the casing 30, and is provided with a squared recess to receive the squared end 37 of the valve stem 38.

This valve stem 38 is provided with a recessed flange 39, in the recess of which is provided a packing ring 40. A compression coil spring 41 is provided in the counterbore of the square portion 37 of the valve stem 38 and bears against the rotary valve 36 to lift the valve stem 38 up against the partition 34. The valve stem 38 is also forced upward by main reservoir pressure air, which is provided in the casing 30 below the partition 34 for urging the rotary valve 36 against its seat in the usual manner.

Rotatably mounted on the valve stem 38 is a gear sector 45, which is in operative engagement with a rack 46 guided by guides 47 and 48, and having its opposite end fastened to a piston 49 contained in the air cylinder 31. A compression coil spring 50 is provided between the piston 49 and the inwardly extending flange 51 of the air cylinder 31. This spring 50 normally maintains the sector 45 in its normal position as shown, but will be compressed to allow the rack 46 to operate the gear sector 45 in a counter-clockwise direction when pressure fluid is admitted to the air cylinder 31.

Directly above the sector 45 the valve stem 38 is provided with a squared portion on

- which is slidably but non-rotatably fitted a valve stem collar C, which is provided with a downwardly extending lug 53 which is adapted to be engaged by the edge of the sector 45 when this sector is rotated in a counter-clockwise direction. This valve stem collar C is provided with a sector of insulation 54, having a contact segment 55 suitably fastened thereto (see Fig. 5). The casing 30 is provided with an insulated terminal board 56 fastened thereto by screws 57, and having resilient contact fingers 58 fastened under the heads of binding posts 59. The relation of the contact segment 55 to that of the contact fingers 58 is such that these contact fingers will be bridged by the segment only if the valve stem collar and rotary valve 36 are in a brake applying position, either service or emergency, or both.
- The valve stem 38 is provided with a cylindrical extension on which is pivotally journaled a handle stem 60, and this handle stem is provided with a flange 61 bearing under the cover 62 screw fastened against the casing 30. This handle stem 60 is provided with a radially extending screw pin 63, which is urged against an upstanding lug 64 on the valve stem collar C by the action of a coil spring 65, this spring having its one end fastened to the handle stem 60 by a screw 66, and having its other end hooked around the curved lug 67 extending from the collar C. It will thus be noted that counter-clockwise rotation of the handle stem 60 causes positive engagement between the screw pin 63 and the lug 64, whereas clockwise rotation of the handle stem 60 provides an operative connection able to transmit a torque equal to the initial tension of this spring 65 only.
- The portion 70 of the handle stem 60 extending from the casing is squared, and provided with the usual brake valve operating handle 71 which is provided with a spring latch 72 adapted to engage suitable notches 73 corresponding to the running, holding, lap and service positions of this handle respectively.
- The flow of air pressure to the air cylinder 31 is controlled by an electrically operated pneumatic valve designated E. P. V. This valve E. P. V. comprises a casing 75, having partitions 76 and 77 to form compartments 78, 79 and 80 respectively. The top wall of the E. P. V. is provided with a threaded opening in which is contained a screw plug 81 which slidably supports the end of a valve stem 82, having an armature 83 fastened to the lower end thereof and adapted to be held in its upper and normal position by a coil 84. This valve stem 82 is provided with valves 85 and 86 adapted to rest on valve seats in the partitions 76 and 77 respectively, the valve 85 being closed when the coil 84 is energized and the valve 86 being closed when this coil is deenergized. The compartment 78 is connected to the main reservoir of the usual air brake system by a pipe 87, whereas the chamber 79 is connected to the air cylinder 31 by a pipe 88, and the chamber 80 is connected to atmosphere through the opening 89. It is thus readily apparent that the air cylinder 31 will be connected to atmosphere when the coil 84 is energized, but will be connected to main reservoir pressure when this coil 84 is deenergized.
- For purposes explained hereinafter, the electro-pneumatic valve E. P. V. is provided with stick contacts, comprising an insulated disk 74 fixed to the stem 82 and engaging insulated stationary contacts, shown as arrows, while the magnet of said valve is energized.
- Operation of brake valve operator.*—Let us assume that the coil 84 of the E. P. V. has been automatically deenergized to effect an automatic service brake application. Under this condition, main reservoir pressure will flow through pipe 87, chambers 78 and 79, through pipe 88 into the air cylinder 31, thereby compressing spring 50 and operating the sector 45 in a counter-clockwise direction.
- Assuming that the brake valve is at this time in its normal running position as shown, the initial or first part of the movement of the gear sector 45 will do nothing toward operating the valve. After this initial movement, the edge of the gear sector 45 will engage the downwardly extending lug 53 on the collar C, thereby carrying this collar C, the valve stem 38 and the rotary valve 36 to the service brake applying position of this valve, the rack 46 being limited from further movement by striking the wall of the casing 30. It will be noted that this movement of the collar C will further tension the spring 65 if the handle 71 will not follow the movement of the collar C. It is contemplated, however, that the initial tension of this spring 65 shall be sufficient so that an automatic operation of the collar C will cause this spring to carry the handle 71 with it to the service position, but will not be strong enough so that if the engineer either holds the handle or moves it to the release position that this spring will prevent the movement of the rotary valve 36 to the service brake applying position by the automatic apparatus.
- Assume now that the engineer has not held the handle 71, and that it has been moved to the service position, so that the spring latch 72 engages the service notch. Assume further that the train has been brought to a safe speed, and that the coil 84 is again energized by the automatic train control equipment to be described hereinafter. The energization of the coil 84 cuts off main reservoir pressure from the air cylinder 31, and connects this cylinder to atmosphere through port 89. The release of pressure from the air cylinder 31 allows the spring 50 to move the rack 46 and gear sector 45 back to their original and normal position. The rotary valve 36 will, how-

ever, not be returned because there is no mechanical connection between the sector 45 and the collar C for clockwise rotation of this sector 45. If the engineer now wishes 5 to release the brakes, he may do so by moving the brake handle to the release position and then to the running position, in the usual manner.

Let us assume now that an automatic service brake application has been effected, as just explained, and that the engineer desires to do still more toward stopping the train. This may be done by operating the brake valve handle 71 to the emergency position, there 15 being no interference between the collar C and the gear sector 45 for counter-clockwise rotation of this collar C. After such a brake application, the brakes may again be released manually in the same manner as heretofore, 20 as soon as the coil 84 is again energized.

Car-carried control apparatus.—In addition to the automatic brake valve operator already described in detail, the car-carried apparatus includes a knock-down car element 25 KD. This car element KD comprises a three-legged core, preferably constructed of laminated magnetic material, comprising a back yoke 90, having legs 91, 92 and 93 terminating in enlarged pole pieces 94. The leg 91 30 of the car element KD is provided with a primary coil P, whereas the legs 92 and 93 are provided with secondary coils S¹ and S² respectively. This car element KD is preferably located on the right side of the vehicle 35 facing in the direction of traffic, and is preferably mounted so that the pole pieces 94 have a definite relation to the track elements with which it is to cooperate. This mounting of the car element is preferably accomplished by housing it in a suitable light non-magnetic casing, suspended from the side frame of the truck, or other suitable part of a vehicle, by an initially tensioned spring device, and having a definite relation with respect to the track.

A reset car element RD is provided which comprises a U-shaped core of magnetic material, having legs 95 terminating in pole pieces 96. A portion of the back yoke of this 50 U-shaped core is preferably cut away to provide an air gap, in which is pivotally supported an armature 97 by a spindle 98 and maintained in its open or retracted position by a spring 99. To this armature 97 is fastened, but insulated therefrom, a movable contact 100, which in the attracted position of the armature 97 is in contact with a stationary contact shown conventionally by the arrow 101. This reset car element RD is 55 preferably supported in a manner similar to the knock-down element KD.

The car-carried equipment also includes two control relays CR¹ and CR², a high speed relay HR, an intermediate speed relay IR, a 60 low speed relay LR in addition to a pickup

relay PR, and a check relay CK. Although these relays have all been shown substantially alike, this showing is merely conventional and in practice the control relays CR¹ and CR² and the pickup relay PR are much more 70 sensitive than the other relays, and operate on less change of current. Each of the relays is especially designed to carry out the function for which it is provided, and are all preferably of the balanced armature type to 75 prevent improper operation due to jars and vibration of the vehicle, and are preferably mounted in a heavy casing supported by springs from the vehicle body. This latter construction causes the jars and vibration of 80 the vehicle to be a certain extent absorbed and transformed by the heavy casing and spring support, thereby preventing such disturbances from reaching the relays and interfering with their operation.

In order to enforce a continuing permissible speed limit, a suitable speed responsive device or governor G has been provided. This governor G comprises a shaft 103 operatively connected to, and driven by, the wheels 90 of the vehicle. On the shaft 103 is pinned a collar 104, and is also slidably supported another collar 105 provided with a peripheral groove 106, which is engaged by an angle lever 107 having an extending arm 108 connected thereto, but insulated therefrom by insulation 109. The collars 104 and 105 are connected together by links 110 and 111, having a weight 112 at the point of their pivotal connection. A compression coil spring 113 100 is provided on the shaft 103 between the collars 104 and 105 for spacing these collars the distance permitted by the links 110 and 111. It is thus seen that upon rotation of the shaft 103, the weights 112 will separate due to the 105 centrifugal force exerted thereon, whereby the collar 105 will be moved downward against the tension of the spring 113, thereby moving the arm 108 toward the right over the stationary contact segments 114, 115, 116 110 and 117.

A suitable pneumatically operated circuit closer has been provided for closing a circuit when the pressure in the brake cylinder of the air-brake system has reached a certain value. 115 This pneumatic circuit closer has been conventionally designated PC, and comprise a cylinder 120 provided with a cover 121 and having a piston 122 fastened to the rod 123 passing through the cover 121. To the end 120 of the rod 123 is fastened, but insulated therefrom, a contact 124 adapted to bridge stationary contacts 125 as the piston 122 is moved toward the left. A compression coil spring 126 is provided between the piston 122 and the cover 121, so that a predetermined amount 125 of pressure in the brake cylinder exerted upon the piston 122 through the pipe 127 is necessary before the contacts 125 will be bridged by the contact 124. It is thus seen, that a 130

circuit may be completed when a predetermined amount of pressure has been applied to the brake cylinder.

Another element of the car apparatus consists of a suitable resetting device by which the engineer, after an automatic brake application, may restore the changed parts of the car equipment. This resetting device is shown in the form of a simple spring reset switch RS having normally open contacts and normally closed contacts. This switch RS is preferably so located as to be accessible only from the ground, in order that the engineer must bring his train to a stop before the switch can be actuated. It should be understood, however, that manipulation of this reset switch RS may be safeguarded in other ways, as by placing it in a locked box, the key of which is held by the conductor or someone else, or by sealing this switch or attaching a recording device, so that the railway officials may tell if this switch has been worked and can discipline the engineer.

Operation of devices shown in Fig. 2.

Under normal conditions, that is, with the vehicle equipped with the apparatus illustrated in Fig. 2 in its normal condition, as shown, and moving in a clear block along a trackway system, such as illustrated in Fig. 1, the primary coil P of the knock-down element KD is energized through a circuit which may be traced as follows:—beginning at the battery 130, wires 131, 132, 133, 134, 135, 136, 137 and 138, primary coil P, wire 139, winding of the check relay CK, wires 140 and 141 back to the common return wire 142 connected to the other side of the battery 130. This check relay CK is provided with a front contact 143 connected in series with the winding and stick contacts of the E. P. V., so that if the current through the primary coil P should be entirely interrupted or should be too low due to depreciation of the battery, or the like, to supply the necessary amount of magneto-motive force in the element KD, this check relay will drop its front contact 143, deenergize the E. P. V., and apply the brakes in the usual manner.

Under normal conditions, the control relay CR¹ is energized through a circuit which may be traced as follows:—beginning at the battery 130, wires 131, 132, 133, 134, 135, 136, 137 and 144, secondary coil S¹, wire 145, winding of the control relay CR¹, wires 146 and 210 to reset switch RS, and wire 211 back to the common return wire 142.

The control relay CR² is energized through a circuit which may be traced as follows:—beginning at the battery 130, wires 131, 132, 133, 134, 135, 136 and 147, secondary coil S², wire 148, winding of the control relay CR², wires 149 and 210, reset switch RS, and wire 211 back to the common return wire 142.

With the control relay CR¹ energized, a stick circuit is completed through the high

speed relay HR which may be traced as follows:—beginning at the battery 130, wires 131, 132, 133 and 150, front contact 151 of control relay CR¹, wire 152, front contact 153 of high speed relay HR, wires 154 and 155, 70 winding of the high speed relay HR, wire 156 back to the common return wire 142.

With the control relay CR² in its energized condition, a stick circuit for the intermediate speed relay IR is completed, which may be traced as follows:—beginning at the battery 130, wires 131, 132 and 157, front contact 158 of the control relay CR², wire 159, front contact 160 of the intermediate speed relay IR, wires 161 and 162, winding of the intermediate speed relay IR, wire 163 back to the common return wire 142. 80

A stick circuit for the low speed relay LR is also completed when either one of the relays CR¹ or CR² is energized, which may be traced as follows:—beginning at the battery 130, wires 131 and 132, either through the front contact 151 of the control relay CR¹ or the front contact 158 of the control relay CR², as the case may be, to wire 164, front contact 165 of the low speed relay LR, wires 166 and 167, winding of the low speed relay LR, wire 168 back to the common return wire 142. It is thus seen that the energizing circuit for the low speed relay LR will only be broken when both the relays CR¹ and CR² are simultaneously deenergized. 95

With each of the relays HR, IR, and LR energized, a high speed circuit for energizing the electro-pneumatic valve E. P. V. 100 is completed, which may be traced as follows:—beginning at the battery 130, wires 131 and 170, front contact 171 of the low speed relay, wires 172 and 173, front contact 174 of the intermediate speed relay IR, wires 175 and 176, front contact 177 of the high speed relay HR, wire 178, high speed contact 117 of the speed responsive device, movable contact 108, wires 179 and 180, front contact 143 of the check relay CK, wire 181, winding of the device E. P. V., wires 182 and 212, stick contact 74 of the E. P. V., and wires 213 and 141 back to the common return wire 142. With this latter circuit completed, the train may assume a speed up to and including, say, sixty miles 110 per hour, as shown in the speed-distance curve illustrated in Fig. 1 of the drawings. 115

Let us assume now that a train equipped with the apparatus illustrated in Fig. 2 is entering the block I when the next block J in advance is occupied by another train. Under this condition, said another train in the block J will shunt the track relay 4¹, thereby causing it to drop its front contact, thereby deenergizing the repeater track relays 17 and in turn 120 open-circuiting the coils 7, 10 and 16 of the track elements T^a, T^b and T^c respectively. 125

As the train passes by the first track element T^a and at the time that this track element bridges the pole pieces of the legs 91 and 92 130

of the knock-down car element KD, a sudden increase of flux will take place through the magnetic circuit including these two legs, this flux again decreasing to its normal value as the car element KD recedes from this track element. This sudden increase and decrease of flux through the secondary coil S^1 , which is partly due to diversion of flux from leakage paths and partly due to a momentary increase of the total flux through the primary coil P, generates a single cycle of E. M. F. in the secondary coil S^1 similar to that of a cycle of alternating current. The secondary coil S^1 is so connected in the circuit with respect to the battery 130 that the first half cycle of this unicycle of E. M. F. will oppose the voltage of the battery 130, thereby decreasing the current flow through the control relay CR¹ sufficiently to cause it to drop its armature and momentarily open its front contact 151. This momentary opening of the contact 151 will interrupt the stick circuit of the high speed relay HR, which will drop its front contact 153 included in this stick circuit, thereby de-energizing this relay HR permanently until reset by some other means. This permanent deenergization of the high speed relay HR permanently interrupts the high speed circuit heretofore traced including the front contact 177 of this relay, and the speed must be below, say, forty-five miles per hour as shown by the dotted line 183 of Fig. 1 in order that the device E. P. V. may receive energy through the intermediate speed circuit, which may be traced as follows:—beginning at the battery 130, wires 131 and 170, front contact 171 of the low speed relay LR, wires 172 and 173, front contact 174 of the intermediate speed relay IR, wires 175 and 184, contacts 116 and 108 of the speed responsive device G, wires 179 and 180, front contact 143 of the check relay CR, wire 181, winding of the device E. P. V., wires 182 and 212, stick contact 74, wires 213 and 141 back to the common return wire 142.

Let us assume now that the train has reached and is passing by the second track element T^b under caution traffic conditions. The passage of the knock-down element KD over this track element T^b causes a sudden increase and decrease of flux through the leg 93 of the car element, similar to the change of flux through the leg 92 as heretofore explained. This sudden increase and decrease of flux induces a single cycle of E. M. F. in the secondary coil S^2 which momentarily de-energizes the control relay CR for reasons heretofore explained in connection with the control relay CR¹. This momentary deenergization of the control relay CR² momentarily breaks the stick circuit of the intermediate speed relay IR, thereby permanently de-energizing this relay due to the opening of the front contact 160 included in its stick circuit. This relay IR will, therefore, remain per-

manently deenergized until again reset by some other means. The deenergization of the intermediate speed relay IR opens its front contact 174, thereby interrupting the intermediate speed circuit through speed responsive contact 116. If the speed is below thirty miles per hour, as indicated by the dotted line 185, the device E. P. V. will be maintained energized through a low speed circuit which may be traced as follows:—beginning at the battery 130, wires 131 and 170, front contact 171 of the low speed relay LR, wires 172 and 186, segment 115 and contact 108 of the speed responsive device, wires 179 and 180, front contact 143 of the check relay CK, wire 181, winding of the device E. P. V. wires 182 and 212, stick contact 74, wires 213 and 141 back to the common return wire 142.

Let us assume that the train continues to pass through the block I under caution traffic conditions between the second and third track elements at a restricted speed of less than thirty miles per hour. When the knock-down car element KD passes over the track element T^c, which is a three-legged element similar to this car element KD, a sudden increase and decrease of flux will take place through both the legs 92 and 93 of this car element KD. This sudden increase and decrease of flux through the secondary coils S^1 and S^2 simultaneously induces a single cycle of alternating current E. M. F. in these coils, the first half cycle of which is in a direction opposing the electro-motive force of the battery 130 and is high enough to momentarily deenergize both the control relays CR¹ and CR². The simultaneous deenergization of both of these relays interrupts the stick circuit for the low speed relay LR heretofore traced. The momentary deenergization of this low speed relay LR causes it to drop its front contact 165 included in its stick circuit, thereby permanently deenergizing it until reset by suitable means. The permanent deenergization of this relay LR interrupts the low speed circuit including the contact segment 115 of the speed responsive device, and the device E. P. V. can be maintained energized through minimum speed contact 114, at a speed such as indicated by the dotted line 187 in Fig. 1 of the drawings, which in the particular case shown is assumed to be fifteen miles per hour. In order to cause substantially the same change of flux through the legs 92 and 93 of the car element KD when passing over the track element T^c, the leg 13 of this track element may be slightly shorter than the leg 14 so that the reluctance through both of the magnetic circuits including the leg 13 and leg 14 respectively may be substantially the same.

The train having now reached the end of the block will be permitted to enter the block J at this low permissive speed of fifteen miles

per hour, unless the block J has changed to a caution or clear block. Let us assume that said another train has passed out of the block J into the following block. Under these conditions, the track relay 4¹ will again be energized, thereby closing the circuit including the battery 24 and coil 23 of the reset track element TR heretofore traced. As the train proceeds and the reset device RD on the vehicle passes over the reset track element TR, flux from the track element TR will permeate the legs 95 of the reset device RD, thereby turning the armature 97, and momentarily completing a circuit through the pick-up relay PR, which may be traced as follows:—beginning at the battery 130, wires 131, 132, 133, 134, 135 and 190, movable contact 100, stationary contact 101 of the reset device RD, wire 191, winding of the pick-up relay PR, wire 192 back to the common return wire 142. The momentary energization of the pick-up relay PR momentarily closes the contacts 193, 194 and 195 of this relay.

The momentary closure of the front contact 195 closes a pick-up circuit for the high speed relay HR which may be traced as follows:—beginning at the battery 130, wires 131, 196, 197 and 198, front contact 195 of the pick-up relay PR, wires 199 and 155, winding of the high speed relay HR, wire 156 back to the common return wire 142. The control relay CR¹ being energized causes the high speed relay HR to become permanently energized after being momentarily energized through the pick-up circuit just traced.

In a similar manner the intermediate relay IR and low speed relay LR may be momentarily energized by the following pick-up circuits:—(1) beginning at the battery 130, wires 131, 196, 197 and 200, front contact 194 of the pick-up relay PR, wires 201 and 162, winding of the intermediate relay IR, winding 163 back to the common return wire 142; (2) starting at the battery 130, wires 131, 196 and 202, front contact 193 of the pick-up relay PR, wires 203 and 167, winding of the low speed relay LR, wire 168 back to the common return wire 142. The relays HR, IR and LR having again been energized, the train is allowed to proceed into the block J, restricted only to the maximum speed limit upon entering, and allows it to pass therethrough in accordance with the speed limits enforced in this block J dependent upon traffic conditions ahead.

In looking at Fig. 1 of the drawings, it will be noted that a step-by-step or saw-tooth speed-distance permissive speed curve will be enforced by the apparatus thus far described. For the particular block shown in Fig. 1, a certain grade, weight of train and braking power being assumed, the speed-distance curve 188 is intended to represent the speeds at various points in the block at which, if a service application of the brakes is initi-

ated, the train will be brought to a stop at or before reaching the end of the block. In other words, the curve 188 represents a brake application curve and shows graphically the speeds at the various points in the block at which the brakes should be applied, either manually or automatically, in order to assure stoppage of the train in time.

The several track elements T^a, T^b and T^c, setting up the different permissive speed limits hereinbefore described, are located along the track with respect to the brake application curve 188 in such a way that a train observing the speed limits automatically prescribed will be controlled on the side of safety. The horizontal lines 183, 185 and 187 represent the speed limits, high, medium and minimum, prescribed by the system. The track inductor T^a is located at such a point, as shown, that a train traveling at the medium speed limit and passing this inductor will, if the brakes are applied, stop before reaching the end of the block. Similarly, the track inductor T^b is located at the point where the high speed limit line 183 intersects the brake application curve 188, and the track element T^c where the maximum speed limit line intersects said brake application curve. It will be evident that the particular location of the various track elements or inductors may be varied to suit the different braking conditions in the several blocks. Also, it should be understood that the speed limits may be different for passenger and freight trains, or trains having different braking powers.

From consideration of the permissive limiting speeds shown in Fig. 1, it can be seen that the step-by-step or saw-tooth line set up represents at some points speeds lower than necessary for safety. For example, at the track inductor T^a, while the speed limit set up at this point is, say, forty-five miles per hour as represented by the line 183, the train could be traveling at higher speeds at several points near said inductor and still be stopped in time. The same is true of the speed limits set up at the inductors T^b and T^c. Consequently, if the engineer is guided by the location of the signal at which he is to stop, and delays his brake application with due regard to his speed and braking power, he is likely to exceed the permissive speed limits set up, more particularly at the track inductors themselves where the permissive speed limits are abruptly changed to lower speed limits. It should also be recognized that the brake application curve 188 will, in the interests of safety, be preferably based in practice upon the worst braked train; and the engineer running a well braked train and knowing the braking power of his train will very likely, if slowing down his train in the usual way to stop at the signal, exceed the speed limits automatically prescribed.

In order to maintain the vigilance of the

engineer, as previously explained, it is considered desirable to impose a penalty every time an automatic brake application occurs, but it will be clear that such penalty can not 5 be fairly and justly imposed unless the engineer has a reasonable opportunity to avoid the automatic brake application. Consequently, if the speed limits required by the 10 automatic train control system are unnecessarily low for safety, as previously explained, the engineer must adopt some unusual way of braking his train, with the resultant decrease in facility of the train movement, or else he is likely to be penalized, although 15 properly controlling the train with due regard to its braking power and the stopping point.

For these reasons, among other things, provision is made according to this invention so 20 that, if the engineer is himself making a manual brake application, or has the brakes applied to a sufficient degree to assure stoppage in time, the speed limits prescribed by the train control system may be exceeded 25 without an automatic brake application and resultant penalty, such suppression or prevention of the automatic brake application existing, however, only so long as the engineer is himself effectively retarding the train, 30 or until the speed has been brought below the permissive speed limits.

Referring to Fig. 2, it can be seen that the electro-pneumatic valve E. P. V. will be maintained energized and an automatic brake application avoided, irrespective of its control 35 by the speed control apparatus, if either of two conditions exist, namely, (a) the engineer's brake valve is in a brake applying position, such as service or emergency, so as to close contacts 58, or (b) there is sufficient pressure in a brake cylinder to close contacts 125. If the engineer's brake valve is in the service position, the brakes are being applied, and since the permissive speed limits and the 40 brake application curve 188 are based upon initiation of the brake application, it can be seen that whenever the engineer places his brake valve in the service position, the train will be stopped in time, even though it is exceeding someone of the permissive speed 45 limits automatically set up. Similarly, if there is effective braking already in force, as manifested by the existence of a predetermined amount of pressure in a brake cylinder, the train is being slowed down and will stop 50 in time. Putting it another way, so long as the train is slowed down, after entering the caution block at a speed less than a maximum entrance speed, it is immaterial whether this 55 result is due to a manual brake application made by the engineer or by an automatic brake application, the train being slowed down in either case.

If the engineer's valve is in the service 60 position closing contacts 58, the electro-pneu-

matic valve E. P. V. is maintained energized, irrespective of the different speed circuits hereinbefore traced, by a circuit that may be traced as follows:—beginning at the battery 130, wires 131, 132, 133, 134 through 70 contacts 58 closed, wires 189 and 180 and through the front contact 143 of the check relay CK, the stick contacts and winding of the E. P. V., as in the circuits previously traced. Similarly, if there is a predetermined pressure in a brake cylinder, sufficient to overcome the spring 126, the contacts 125 are bridged by the contact member 124, establishing a circuit for energizing the device E. P. V. analogous to the circuit just so traced.

To illustrate the advantages of the arrangement by which the engineer, by making a manual brake application, may forestall or suppress automatic braking, assuming the 85 train exceeds the maximum normal running speed, if the engineer, realizing that his train is running too fast, has initiated a brake application, or already made a brake application, the movement of contact 108 out of engagement with contact 117 does not deenergize the electro-pneumatic valve E. P. V., which is maintained energized through the closure of contacts 58 or 125, as the case may be. With the brakes being applied or fully 95 acting, it is obvious that the train must in time reduce its speed below the maximum permissive speed, whereupon contacts 108—117 reclose. After the speed has been brought down below the maximum normal running speed desired, then the engineer may release the brake application; but if the engineer should fail to apply the brakes or maintain the brakes applied until the desired maximum speed limit has been observed, then the electro-pneumatic valve 100 E. P. V. will be operated, and an automatic 105 brake application occur.

Assume now that the train enters the block I show in Fig. 1 under caution conditions at a speed of, say, fifty-five miles per hour. This speed is higher than the speed limit of forty-five miles per hour automatically set up at the track inductor T^a. If the engineer is alert and observes that he has 110 passed a caution signal, and realizing that his speed is too high, initiates a brake application before passing the track element T^a, the brakes will not be automatically applied, even though the speed is above the permissive speed indicated by the line 183; and if the engineer properly maintains this brake application, the speed of the train will be reduced in the manner indicated by the dot and dash curve 205 as a typical example. If 115 the train has more braking power than indicated by the application curve 188, the speed under the manual brake application 120 will be reduced faster than shown by the curve 205, but in any case the train will keep 125 the curve 205, but in any case the train will keep 130

below the application curve 188. If the engineer releases the brakes before his speed has been reduced down to that indicated by the line 183, an automatic brake application 5 occurs; but if the engineer keeps the brakes on until the speed has been so reduced, he may then release them if he desires. Similarly, a train may approach and pass the track element T^e at a speed greater than 10 thirty miles per hour, as indicated by the line 185, without receiving an automatic brake application, providing the engineer has initiated or made a full service application, the train then traveling along the line shown in 15 206 as a typical instance. The same thing is true for the inductor T^e .

If both of the series or group of circuits by 20 which the electro-pneumatic valve E. P. V. may be maintained energized, that is, those through the contacts 114—117 of the speed responsive device G, and those through the contacts 58 or 125, are at any time broken and said valve is deenergized, its stick contacts 74 open, so that subsequent closure of either of 25 these groups of circuits does not permit reenergization of said valve, which must be reset by manipulation of the reset switch RS. Consequently, whenever the electro-pneumatic valve E. P. V. operates to stop the train, 30 the engineer is obliged to stop and reset from the ground, this being the penalty for his failure to safely control the train. It will be noted that the reset switch RS, when actuated to close its normally open contacts, provides 35 a shunt for the stick contacts 74 of the device E. P. V. permitting this device to be picked up by one of its normal energizing circuits. Since the train must be at a standstill or must be moving very slowly in order to allow the 40 reset push button RS to be operated, the contact 108 is in engagement with segment 114, and with push button RS depressed the following reset circuit is closed:—beginning at battery 130, wires 131, 132 and 132^a, contacts 45 114—108, wires 179 and 180, front contact 143 of the check relay CK, wire 181, winding of the device E. P. V. wires 182 and 182^a, depressed contact RS, wires 211 and 142 back to the other side of the battery 130. The reset 50 switch RS can not be maliciously fastened down, because when it is shifted, its normally closed contacts open and deenergize both of the relays CR¹ and CR², thereby establishing the minimum speed limit. In other words, if 55 the engineer should endeavor to defeat the objects of the invention and avoid the penalty by fastening down the reset switch RS, his train can not proceed above a minimum speed. Obviously, other expedients for protecting 60 this reset device RS may be employed; and generally speaking, this switch, when actuated, may break any vital circuit limiting the speed of the train or preventing it from moving at all until said switch is restored to normal.

From the foregoing it can be seen that there is provided by this invention the simple and efficient arrangement in which, if the engineer is alert and whenever his speed becomes too high makes a manual application of the 70 brakes, there is no automatic braking, while if the engineer is negligent, either by exceeding normal speed, by failing to observe the restrictive signal indications and reduce speed accordingly, or by neglecting at any time to 75 maintain safe speeds or apply the brakes, an automatic application of the brakes is made to safeguard the train and the engineer is penalized for his neglect. Thus, not only is vigilance on the part of the engineer stimulated 80 and in fact enforced in a practical manner, but the train is at all times automatically controlled on the side of safety, all this being accomplished without particular refinement in prescribing permissive speed limits for various blocks. Also, since the automatic application of the brakes will occur very rarely, since 85 engineers as a rule are alert and careful, the automatic brake application may be somewhat severe in its effect on the equipment, 90 sliding the wheels, producing considerable jar and shock, and the like, because this automatic application will occur so rarely and then only in the event of a real emergency 95 due to failure of the engineer, that these effects may be tolerated.

Description of Fig. 6.—In Fig. 6 has been illustrated a modified form of the invention shown in Fig. 2 in which the car-carried devices and circuits are substantially the same with the exception of the knock-down car elements. Like devices and circuit wires have therefore been given the same reference characters. The principal distinction of this system from that of the one shown in Fig. 2 resides in the provision of two knock-down car 100 elements: KD¹ and KD² instead of the single knock-down car element KD shown in Fig. 2. These knock-down car elements KD¹ and KD² comprise U-shaped cores of magnetic 105 material terminating in enlarged pole pieces, on the one leg of which is provided a primary coil P^b, the other leg of the element KD¹ being provided with a secondary coil S^{1b}, whereas the car element KD² has its other leg provided with a secondary coil S^{2b}. These primary coils P^b are connected in series and in a 110 circuit substantially the same as the primary coil P in Fig. 2, whereas the secondary coil S^{1b} has been substituted for the secondary coil S¹ and the secondary coil S^{2b} has been 115 substituted for the secondary coil S².

Another distinction in the car-carried apparatus of this figure resides in the location of the reset device RD with respect to the 120 trackway, that is, it is located between the running rails instead of being located on the left side of the vehicle, as shown in Fig. 2. Similarly, the trackway devices have been modified to properly cooperate with the car- 125

carried devices, the reset track device TR being located between the running rails, while U-shaped track elements TH located on the right side of the trackway and track elements 5 TI located on the left side of the trackway have been provided to transmit a high speed knock-down influence and an intermediate speed knock-down influence respectively, whereas a pair of U-shaped track elements 10 TL, one located on each side of the trackway have been provided for transmitting a low speed knock-down influence. Each of these track elements are provided with coils which under clear traffic conditions may be closed 15 in a circuit of low resistance, substantially in the same manner as described in connection with Figs. 1 and 2. If desired, these track elements may be unsymmetrically spaced with respect to the track rails so that 20 the vehicle equipped with the knock-down elements KD¹ and KD² will not properly cooperate therewith after this vehicle is turned end for end. The operation of the system shown in Fig. 6 is substantially the 25 same as that of the system in Fig. 2, and will be obvious to those skilled in the art after understanding the operation of the preferred embodiment of this invention.

Although only two specific embodiments 30 of the present invention have been illustrated, it should be understood that various modifications may be used to adapt the invention to various conditions encountered in practice without departing from the spirit and 35 scope thereof. For instance, the trackway devices may be controlled in any suitable manner dependent upon the block signal system in connection with which they are used, that is, may be controlled entirely automatically using various forms of electrical 40 energy for this purpose, or may be partly controlled manually; or certain of the trackway devices may be made permanently effective so as to enforce lower speed limits through 45 territory which has permanent hazards, such as curves, sudden down grade sections, draw-bridges, and the like. Further, the car-carried apparatus may be modified to apply it to the various trackway systems employed. 50 For instance, the necessary modification may be made so that the same apparatus can be used when either end of the vehicle is running ahead, either for double track or single track systems, so that no control influence 55 will be received when running against the normal direction of traffic in either case; as is obvious to those skilled in the art.

While there has been shown and described 60 specific apparatus performing certain functions for accomplishing automatic speed control of railway vehicles, this invention in a broader aspect represents a method of safeguarding train movements, such method having well defined characteristics conceivable 65 independently of any particular form of ap-

paratus. To illustrate, irrespective of the particular equipment employed on the trackway or on the car, the invention in its broad aspect contemplates safeguarding the movement of the train and at the same time maintaining vigilance on the part of the engineer by establishing at appropriate points along the track certain permissible speed limits, the change from one permissive speed limit to another being abrupt and not necessarily in 70 conformity with the possible rate of retardation of the train, and in automatically applying the brakes if any one of these speed limits is exceeded at any time, unless the engineer anticipates such automatic brake application 75 by manually initiating an application and maintaining an effective braking until the speed of the train has been brought down below the existing permissive speed limit, and finally in imposing a penalty upon the engineer at the same time in the event that an 80 automatic application of the brakes occurs.

Having now fully shown and described my invention, what I desire to secure by Letters Patent, is:—

1. In an automatic train control system for railway cars or other vehicles traveling on tracks divided into blocks, each having a track circuit, car equipment comprising, a 90 brake-setting appliance acting automatically upon the regular or brake equipment of the car to produce a brake application, said appliance when operated maintaining the brakes applied until restored, means for restoring said appliance effective only after the car has been brought to a stop, apparatus including a speed responsive device driven from the car wheels and controllable to cause any one of several predetermined permissive speed limits to be set up until there is a 95 change to a higher or lower speed limit, said apparatus making the change from one existing speed limit to another quickly and acting to cause operation of said brake-setting appliance if the car at any time exceeds the permissive speed limit then in effect, track elements of different construction located at selected points in each block and in the active condition if the next block in advance is occupied, car carried receiving means 100 separately and selectively influenced inductively through an intervening air gap by said track elements while in their active condition, and when so influenced acting to control said apparatus and set up a corresponding speed limit, means on the car effective only if the engineer's brake valve is placed in the service position before said brake setting appliance operates for preventing any 105 operation thereof so long as the brake valve is kept in that service position, and other means effective only so long as the brakes are applied to a prescribed degree for preventing initial operation of said brake setting appliance. 110

2. In a train control system for railroads, car equipment comprising, in combination with the usual air-brake equipment, means for producing an automatic application of the brakes and including an electro-responsive device, said electro-responsive device having stick contacts closed only if said device is energized, a normally closed circuit for energizing said device, including stick contacts and having a plurality of multiple branches, said device whenever deenergized maintaining the brakes applied until restored, means for restoring said device only after the car has been brought to a stop, means controllable from the trackway and including a speed responsive device driven from the car wheels for cooperating with the multiple branches of said normally closed circuit to provide any one of a plurality of predetermined persisting speed limits and to automatically deenergize said electro-responsive device and apply the brakes whenever the car exceeds the speed limit then in effect, and means effective only if the engineer's brake valve is in the service position for establishing an auxiliary stick circuit for said electro-responsive device and thereby prevent operation thereof, providing the engineer's brake valve is placed in the service position before said electro-responsive device is initially deenergized on account of excessive speed. 70
3. In an automatic train control system, the combination of a railway vehicle and a trackway therefor divided into blocks, of car-carried apparatus adapted to restrict the speed of the train in a block when the next block in advance thereof is occupied comprising, means for setting up speed limits by the transmission of inductive control influences from the trackway, each speed limit persisting until followed by a lower speed limit or until a release influence is transmitted from the trackway, means for automatically applying the brakes of the train if the speed of the train is in excess of the permissible speed, and means effective only if a brake application is being initiated or when an adequate brake application has been effected and as long as such a brake application continues for preventing initial operation of said brake applying means. 75
4. An automatic train control system for railways having a trackway divided into blocks comprising; means for setting up successive lower speed limits in a block when the next block in advance thereof is occupied by transmitting inductively through an intervening air gap distinctive control influences at appropriate control points in a block for each speed limit, such speed limit persisting until the next lower speed limit is set up to form a step-by-step or saw-tooth permissible speed-distance curve of a character so that if the brakes are applied when the speed of the vehicle does not exceed that of the curve at any point in the block, the train will be retarded sufficiently to have its speed fall below the top teeth of this curve; means for automatically applying the brakes when the permissive speed is exceeded; and means for rendering said last mentioned means ineffective only if an application of the brakes is being manually initiated or only if the brakes are applied to a predetermined extent, whereby the train may run at a speed above the lower points but not above the upper points of said speed-distance curve without an automatic brake application. 75
5. In a train control system for railway vehicles equipped with an air-brake system and traveling over tracks divided into blocks, an automatic brake setting appliance acting upon the air-brake system to produce an automatic brake application, apparatus on the vehicle including a speed responsive device driven from the car wheels and controllable to provide any one of three or more speed limits and actuate said appliance if the vehicle at any time exceeds the speed limit then in force, means comprising, a car-carried receiving element and trackway elements cooperating therewith inductively through an intervening air gap for controlling said apparatus under one of its speed limit conditions, said trackway elements being differently constructed and acting separately and selectively upon said apparatus through said receiving element, said brake-setting appliance after initial operation thereof maintaining the brakes applied until restored, means effective only after the vehicle has been brought to a stop for restoring said appliance, and means effective only if the engineer's brake valve is placed in the service position prior to initial operation of said appliance for preventing the operation thereof, whereby the engineer by taking the necessary action prior to exceeding the speed limit may release the brakes as soon as the existing speed limit has been observed without being obliged to come to a stop. 90
6. In an automatic train control system, the combination of a plurality of inductive influence transmitting devices along the trackway, each having a magnetic structure physically different from that of the magnetic structures of any other of said influence transmitting devices, each of said devices including a winding, a car-carried influence receiving device adapted to function distinctively upon the reception of an influence from each of the distinctive track devices, and means for including said winding in a closed deenergized circuit of low resistance. 105
7. In an automatic train control system, a car-carried electro-magnetic impulse receiving means comprising, a yoke, a primary and secondary coil on said yoke, a circuit including a source of energy for said primary coil, 110
- 120
- 125
- 130

- a circuit for each of said secondary coils each including an electro-responsive device, and a plurality of magnetic devices each having distinctive physical characteristics for transmitting distinctive control influences to said car-carried element.
8. In an impulse transmitting means for automatic train control systems, a car-carried element comprising a yoke having three-spaced legs on the same plane, and energized coil on one outside leg tending to send flux through each of the other legs, electro-responsive means associated with each of said other legs and separately operated by changes in the magnetic flux in the corresponding leg, and different track elements for cooperating with said car-carried element to produce operation of said electro-responsive means, separately or simultaneously.
9. In an automatic train control system, the combination with a car-carried impulse device including a plurality of partial magnetic circuits, a plurality of control devices operable upon a quick change in reluctance in one or more of said magnetic circuits, and traffic controlled trackway devices comprising inert magnetic bodies of different physical characteristics, whereby distinctive changes of reluctance may be effected upon one or more of said magnetic circuits.
10. In an automatic train control system, the combination of vehicle-carried apparatus comprising, two control relays and three stick relays; means for deenergizing one of said stick relays when one of said control relays is momentarily deenergized, for deenergizing another stick relay when the other of said control relays is momentarily deenergized, and for deenergizing a third stick relay only if both of said control relays are simultaneously deenergized; and of trackway devices for selectively momentarily deenergizing one or more of said control relays.
11. In an automatic train control system, a vehicle and a trackway therefor divided into blocks each provided with a normally closed track circuit, means for transmitting controlling influences from the track to the vehicle inductively through an intervening air-gap, comprising a plurality of controllable initiating impulse devices of different physical construction and operating characteristics in each block for independently and selectively initiating the operation of a plurality of car-carried devices, a separate resetting device at the exit end of the block, said initiating devices being made effective by interrupting a circuit associated therewith, and said resetting devices being made effective by closing a circuit including a source of energy, whereby the interruption of any of said circuits will produce an effect on the side of safety.
12. In an automatic train control system, the combination of car-carried equipment for applying the brakes automatically if a predetermined permissive speed limit set up has been exceeded, of trackway equipment comprising blocks each having a plurality of inductive influence transmitting devices of different physical characteristics for setting up different permissive speed limits, each of said devices having a coil which if closed in a circuit of low resistance will prevent it from functioning, and a trackway device near the exit end of such block including a coil and adapted to remove such restrictive speed limits if said coil is closed in a circuit with a suitable source of energy.
13. Trackway equipment for transmitting inductive control influences to suitable receiving devices on a railway vehicle for train control systems comprising, a plurality of devices along the trackway each of which is constructed to transmit a restrictive control influence distinctive from that of the other trackway devices provided a circuit associated therewith is interrupted, and another trackway device for transmitting a release influence if a circuit associated therewith is completed.
14. An automatic train control system comprising, a brake control device on a vehicle which if initiated will continue to apply the brakes effectively until restored, means accessible only from the ground for restoring said device, and means for enforcing a low speed limit which the vehicle can not exceed without an automatic brake application automatically rendered effective when and so long as said restoring means is in its restoring condition even though traffic conditions ahead are favorable.
15. Car-carried apparatus for automatic train control systems comprising, two normally inactive circuit interrupting devices adapted to be actuated by influences transmitted from the trackway, two stick relays each having a stick circuit including a contact closed only when such relay is in the energized position, one of said circuits including a contact of one of said circuit interrupting devices and the other stick circuit including a contact of the other circuit interrupting device, and a third stick relay having a stick circuit including its front contact and including two contacts in multiple operated separately by said two circuit interrupting devices, whereby momentary operation of one of said circuit interrupting devices drops one of said stick relays, the momentary operation of the other circuit interrupting device drops another stick relay and momentary simultaneous operation of both of said circuit interrupting devices drops the third relay.
16. Car-carried apparatus for automatic train control systems comprising, a stick relay having a stick circuit including a front contact of said relay which if deenergized restricts the speed of the vehicle, may travel

without incurring an automatic brake application, means for applying the brakes if the speed imposed with the stick relay in the de-energized position is exceeded, means for de-energizing said stick relay including an inductive influence receiving device provided with a secondary coil in which a current is induced by inductive communication of said inductive communicating device with a suitable trackway device, and means for picking up said stick relay including an armature adapted to be actuated by a flux producing means disposed along the trackway.

17. Car-carried apparatus for automatic train control systems comprising, a stick relay normally energized by a stick circuit, including a front contact of said relay, means acting on the usual air brake system for applying the brakes if the vehicle exceeds predetermined speed limits when said relay is de-energized, means for deenergizing said stick relay, and means for again picking up said stick relay by momentarily closing a pick-up circuit, said pick-up circuit including a contact closed if an armature adapted to be actuated by a flux producing means disposed along the trackway when active.

18. Car-carried equipment for automatic train control systems comprising, a normally energized electrically operated stick brake control device having a circuit including a contact operated by said device and closed only when said device is energized and which device if deenergized effects an application of the brakes by acting on the usual air brake system, circuit controlling means in series with said circuit for breaking said circuit if a certain speed limit is exceeded including means controlled from the trackway in accordance with traffic conditions ahead for abruptly changing such speed limit, two contacts in multiple with said circuit controlling means one of which is closed when the engineer's brake valve is in a brake applying position and the other of which is closed when a full service brake application is effective, whereby if and only if the engineer anticipates the excessive speed by the initiation of a manual brake application an automatic brake application may be prevented.

19. Car-carried equipment for automatic train control systems comprising, a normally energized electrically operated stick brake control device having a circuit including a contact operated by said device and closed only when said device is energized and which device if deenergized effects an application of the brakes by acting on the usual air brake system, circuit controlling means in series with said circuit for breaking said circuit if a certain speed limit is exceeded including means controlled from the trackway in accordance with traffic conditions ahead for abruptly changing such speed limit, two contacts in multiple with said circuit controlling means

one of which is closed when the engineer's brake valve is in a brake applying position and the other of which is closed when a full service brake application has been made effective, whereby if and only if the engineer anticipates the excessive speed by the initiation of a manual brake application an automatic brake application may be prevented, and means for penalizing the engineer each time an automatic brake application occurs.

20. In an automatic train control system, the combination of a railway vehicle and a trackway therefor divided into blocks, of car-carried apparatus adapted to restrict the speed of the train in a block if the next block in advance is occupied comprising, means for setting up different permissive speed limits by correspondingly distinctive control influences transmitted inductively from the trackway, each speed limit persisting until followed by a lower speed limit or until a release influence is transmitted from the trackway, means for automatically applying the brakes of the vehicle if the speed then existing of the vehicle is in excess of the permissive speed, and means for preventing release of such brake application until the train has been brought to a stop unless the engineer has initiated a manual brake application before the permissive speed of the vehicle was exceeded.

21. In an intermittent inductive impulse transmitting means for train control systems capable of giving a plurality of controls, a car-carried receiver comprising a magnetic body providing two separate partial magnetic circuits, an energizing coil common to said magnetic circuits acting to send flux through both, coils separately associated inductively with said magnetic circuits, electro-responsive devices on the car separately connected to said coils and independently influenced by the voltages induced in said respective coils by flux changes in the corresponding magnetic circuits, a trackway element cooperating with said receiver to reduce the reluctance of one of said magnetic circuits, another trackway element acting to reduce the reluctance of both of said magnetic circuits simultaneously, and windings on said trackway elements and control circuits therefor governed in accordance with traffic conditions.

22. An automatic train control system comprising, vehicle carried apparatus including a brake control device, a speed responsive device driven from the wheels of the vehicle, a relay on the vehicle, means effective when said relay is de-energized for applying the brakes of the train by actuating said brake control device if the actual speed as manifested by said speed responsive device exceeds a predetermined speed limit, means partly on the vehicle and partly along the trackway for transmitting control influences from the trackway to the vehicle inductively through

- an intervening air gap in accordance with traffic conditions ahead for energizing and de-energizing said relay, manually operable means which if moved to its active position 5 will prevent said brake control device being rendered active, and means for preventing said manually operable means being left in its active position permanently consisting of means for de-energizing said relay to impose 10 said speed limit so long as said manually operable means assumes its active position.
23. An automatic train control system comprising, a normally energized electrically operable brake control device on the vehicle 15 which if operated automatically co-operates with the air brake system of the vehicle to produce an automatic brake application, said device once operated preventing release of the brakes until specially restored, means ac- 20 cessible only from the ground for restoring said device after operation thereof to permit release of the brakes, apparatus on the vehicle including a speed responsive device driven from the wheels of the vehicle and 25 controlled inductively through an intervening air gap from the trackway in accordance with traffic conditions, said apparatus automatically actuating said brake control device whenever the vehicle exceeds a predetermined 30 speed limit under unfavorable traffic conditions, and automatic means for preventing such operation of said brake control device notwithstanding the excessive speed of the vehicle only if the engineer initiates and com- 35 pletes a predetermined manual application of the brakes prior to exceeding said speed limit.
24. An automatic train control system comprising, a brake control device on a vehicle, including a normally energized electropneumatic valve adapted when de-energized to cause an automatic brake application, said device when once operated continuing in operation and preventing release of the brakes until specially restored, means effective only if the vehicle has been brought to a stop for re- 40 storing said device, a relay on the vehicle, means partly on the vehicle and partly on the track for controlling said relay automatically in accordance with traffic conditions, means on the vehicle including a speed responsive 45 device driven from the wheels thereof and governed by said relay for controlling said brake control device, said last mentioned means acting while said relay is de-energized to actuate the brake control device whenever 50 the running speed of the vehicle exceeds a predetermined speed limit, an engineer's 55 brake valve, pressure responsive means actuated only if a predetermined brake application is in force, and means effective only if 60 said engineer's brake valve is in a brake applying position or said pressure responsive means is actuated prior to the automatic operation of said brake control device for preventing operation thereof in spite of the ex- 65 cessive speed of the vehicle.

In testimony whereof I hereto affix my signature.

WINTHROP K. HOWE.
